CLAIM

The ornamental design for a combined eyelash comb and case, as shown and described.

DESCRIPTION

FIG. 1 is a top perspective view of a combined eyelash comb and case showing my new design;

FIG. 2 is a front elevational view thereof;

FIG. 3 is a side elevational view thereof;

FIG. 4 is a rear elevational view thereof, showing a partial portion of the teeth of the comb for ease of illustration;

FIG. 5 is a top plan view thereof;

FIG. 6 is a bottom plan view thereof; and

FIG. 7 is a top perspective view thereof, showing the comb retracted into the case.
